UNITED STATES PATENT OFFICE.

JAMES W. PEIRCE AND CHARLES L. HANNAH, OF ORANGE, TEXAS; SAID PEIRCE
ASSIGNOR TO OSCAR SIMONS TAM, OF ORANGE, TEXAS.

SILO.

1,210,688.

Specification of Letters Patent.

Patented Jan. 2, 1917.

Application filed July 26, 1915. Serial No. 41,984.

To all whom it may concern:

Be it known that we, JAMES W. PEIRCE and CHARLES L. HANNAH, citizens of the United States of America, residing at 5 Orange, in the county of Orange and State of Texas, have invented certain new and useful Improvements in Silos, of which the following is a specification, reference being had therein to the accompanying drawing.

10 This invention relates to silos and has for its object the production of a simple and efficient means for connecting the silo blocks.

Another object of this invention is the production of a simple and efficient means 15 for holding the blocks in an assembled position.

With these and other objects in view, this invention consists of certain novel combinations, constructions, and arrangements of 20 parts as will be hereinafter fully described and claimed.

In the accompanying drawings, Figure 1 is a front elevation of a portion of a silo. Fig. 2 is a transverse sectional view through 25 a series of the blocks, showing the manner in which the blocks are connected together.

By referring to the drawings it will be seen that a body 31 is employed mounted upon the base 32, the bottom blocks being 30 held in engagement with the base 32 by means of the hooks 33.

A framework 34 is placed upon the silo for forming a door-way which may be closed in any suitable manner such as the common 35 type of sealing doors used upon such devices as silos, refrigerators, and the like.

The body of the silo as illustrated is preferably formed in octagonal shape and is formed of a plurality of blocks and each 40 block is provided with a dove-tailed socket 35 at one end and a dove-tailed tongue 36 at its opposite end, the dove-tailed tongues being fitted within the sockets 35 of the adjacent section. A corner strip receiving 45 socket 37 is formed near the rear face of each block 38 and when the blocks are assembled together, a substantially dove-tailed socket will be produced upon the inner corner or joint of the blocks. The dove-tailed 50 corner strip 39 is then seated within the sockets 37 and constitutes a very simple and efficient means for reënforcing the joint

connection between the silo blocks 38, and also for producing a smooth joint along the inner corner of the silo.

It should be understood that the silo as illustrated is especially adapted to be made of wood or other suitable material to permit the silo to be readily disassembled and erected with the minimum amount of labor.

55 The blocks 38 are provided with centrally located apertures 40 for the purpose of receiving the vertically extending tie rods 41 passing through the apertures 40 for holding the several blocks in vertical alinement with 60 each other.

65 It should be understood that all of the several parts of the present invention go to make up a complete and unitary structure, the construction of the blocks being essential 70 to the construction of the particular building desired.

What we claim is:—

75 1. A silo of the class described comprising a body formed of a plurality of similarly constructed blocks, said blocks provided with interlocking dove-tailed portions, said blocks also provided with dove-tailed sockets upon the inner face thereof adjacent the abutting ends of said blocks, a dove-tailed corner 80 strip fitting in said sockets, and vertically extending tie rods passing through said blocks for holding the same in vertical alinement.

85 2. A silo of the class described comprising a body formed of a plurality of similarly constructed blocks, each block provided with a dove-tailed tongue upon one end thereof and a dove-tailed socket upon the opposite end thereof, the abutting ends of said blocks 90 being cut on an angle to the longitudinal axis thereof, each block provided with a substantially V-shaped notch formed upon the rear face adjacent each end thereof, an interlocking vertically extending bar fitting 95 within the adjoining V-shaped notches of the abutting blocks and constituting an efficient seal for the inner corners of said blocks, and tie rods passing longitudinally of said blocks.

100 In testimony whereof we hereunto affix our signatures.

JAMES W. PEIRCE.
CHARLES L. HANNAH.
